UNITED STATES PATENT OFFICE.

REINHARD E. BARTELS, OF LYNN, MASSACHUSETTS.

METHOD AND MEANS FOR FIXING SHANK STIFFENERS IN SHOES.

Application filed June 12, 1924. Serial No. 719,678.

To all whom it may concern:

Be it known that I, REINHARD E. BARTELS, a citizen of the United States, residing at Lynn, in the county of Essex and State of Massachusetts, have invented new and useful Improvements in Methods and Means for Fixing Shank Stiffeners in Shoes, of which the following is a specification.

This invention relates to shank stiffeners and the method of fixing them in shoes, relating more especially to the attachment of the stiffeners at their forward ends. Their forward ends are located adjacent to the "break" line of the sole and it is important that no portion of the attaching means should project above the surface of the innersole at this point in a manner to cause discomfort to the wearer. The fastener is attached while the shoe is on the last and at this part of the last there is no metal plate as at the heel against which stiffener fastening means driven through the innersole may be clinched.

This invention, therefore, provides a metallic device positioned on the inner face of the innersole and bearing on the last and which serves as an anvil for supporting an innersole where the fastener is to be clinched. This not only insures proper clinching of the fastener but also prevents it from presenting a rough projection on the interior of the shoe and also from injuring the last.

For a more complete understanding of this invention reference may be had to the accompanying drawings in which—

Figure 1 is an inverted plan of a lasted welt shoe showing the anvil member in position.

Figure 2 is a fragmentary section on line 2—2 of Figure 1.

Figure 3 is a view similar to Figure 1, but showing the shank stiffener in position ready to be fixed to the innersole.

Figure 4 is a fragmentary section on line 4—4 of Figure 3.

Figure 5 is a section to a larger scale on line 5—5 of Figure 4.

Figure 6 is a section on line 6—6 of Figure 5.

Figure 7 is a view similar to Figure 5, but showing the stiffener fixed to the innersole.

Figure 8 is a fragmentary section on line 8—8 of Figure 7.

In carrying out this invention at the point where the forward end of the shank is to be attached, the innersole 1 is perforated, as

shown at 10 in Figure 1, and before the innersole is tacked to the last a headed metallic member 11 has its shank 12 passed through this perforation, the head of this member resting against the inner face of the innersole so that when the innersole is tacked to the last it bears between the surface of the last and the innersole, as shown clearly in Figure 2. This headed member 65 may be of any suitable description, but a round headed paper fastener such as is commonly employed to fasten sheets of paper together has been found suitable. Such a fastener comprises a narrow metal strip 70 folded on itself to form a flat intermediate portion *a* (Figure 5) over which a round head *b* engages, the ends of the strip forming a split shank which may be separated and the ends bent down on to the material 75 through which the shank is passed.

After the shoe has been lasted and it is desired to fix the shank stiffener in position, it is placed on the exposed face of the innersole as shown in Figures 3 and 4. The 80 shank stiffener is provided with a perforation 15 through which the shank 12 of the paper fastener, or other headed member, may extend, and projecting from the face of the stiffener adjacent to the innersole are shown a pair of integral attaching prongs 16. By pressing these from the body of the shank stiffener, the hole 15 through which the shank of the headed member extends, is formed at the same time. It will be noted 85 also that these clinching points or prongs are sufficiently close together to lie within the area of the head of the headed member and at opposite sides of its shank. The head thus serves as an anvil for these prongs 90 when they are driven into the innersole as shown in Figures 7 and 8. At the same time that these attaching prongs are driven into the innersole the shank of the headed member may be bent down against the exposed 100 face of the stiffener. Where a paper fastener is used as the headed member, the opposite ends of the strip of sheet metal comprising the shank of the fastener are separated, the two ends being bent slightly in opposite directions, so that by striking a single blow with the hammer these ends are bent down against the shank stiffener as shown at 17 and 18 in Figure 7, at the same time that the attaching prongs 16 are 105 driven into the innersole. The same blow also acts to flatten out the head of the paper 110

fastener so that it offers no objectionable projection on the inner face of the innersole.

The rear end of the shank stiffener may be provided with prongs 20 which may be driven into the innersole to fix this end of the stiffener in position in the usual manner.

As herein shown the stiffener comprises two strips of sheet material 25 and 26 fixed in face to face relation, the strip 25 having its central portion laterally curved to form a beaded portion 27 extending longitudinally thereof. It might be otherwise constructed, however, without departing from the spirit or scope of this invention. Likewise in place of forming the prongs 16 integral with the stiffener other fastening means for the forward end of the shank stiffener may be employed, provided they are of such a nature that they may be clinched within the area of the headed member so that this may serve as an anvil therefor.

Having thus described an embodiment of this invention it should be evident to those skilled in the art that various changes and modifications might be made therein without departing from its spirit or scope as defined by the appended claims.

I claim:

1. The method of attaching shank stiffeners to shoes which comprises inserting the shank of a headed metallic member through a sole member of the shoe, the head being on the opposite side of the sole member from the stiffener, placing the stiffener in position and inserting fastenings for said stiffener into the opposite side of the sole member from said head and clinched within the area thereof.

2. The method of attaching shank stiffeners to shoes which comprises inserting the shank of a headed metallic member through a sole member of the shoe, the head being on the opposite side of the sole member from the stiffener, placing the stiffener in position with fastenings at the opposite side of the sole member from said head to be clinched in said sole member within the area of said head, and bending the shank of said headed member over the exposed face of said stiffener and clinching said fastenings.

3. The method of fixing a shank stiffener to an innersole which comprises inserting the shank of a headed metallic member through the innersole at a desired fastening point with its head lying on the upper face thereof before the sole is tacked to the last, and after the lasting operation placing a pronged shank stiffener in position on the outer face of the innersole with the prongs opposite to said head, and driving the prongs into the innersole within the area of said head.

4. The method of fixing a shank stiffener to an innersole which comprises inserting the shank of a headed metallic member

through the innersole at a desired fastening point with its head lying on the upper face thereof before the sole is tacked to the last, and after the lasting operation placing a pronged shank stiffener in position on the outer face of the innersole with the prongs opposite to said head, and driving the prongs into the innersole within the area of said head and bending the shank of said headed member over said stiffener.

5. The method which comprises perforating an innersole adjacent to its "break" line, inserting through said perforation from the inner side of said innersole the shank of a headed metallic member, placing on the outer side of said innersole a shank stiffener having a prong pointing toward said innersole, and a perforation through which said shank passes, said prong lying within the area of the head of said member, and then striking said shank and stiffener to bend said shank over the exposed face of said stiffener and to drive said prong into said innersole to fix the forward end of said shank fastener in position.

6. The method which comprises perforating an innersole adjacent to its "break" line, inserting through said perforation from the inner side of said innersole the two-part shank of a headed metallic member, placing on the outer face of said innersole a shank stiffener having a prong pointing toward said innersole and a perforation through which said shank passes, said prong lying within the area of the head of said member, separating the parts of said shank, and then striking said shank and stiffener to bend the parts of said shank over the exposed face of said stiffener and to drive said prong into the innersole to fix the forward end of said stiffener in position.

7. A shoe comprising a sole member having a perforation adjacent to its "break" line, a headed fastener having its shank portion extending through said perforation, its head lying against one face of said sole member, a shank stiffener having a perforation adjacent to its forward end through which said shank passes, and fastening elements for said stiffener extending into said sole member toward said head and within the area thereof.

8. A shoe comprising a sole member having a perforation adjacent to its "break" line, a headed fastener having its shank portion extending through said perforation, its head lying against one face of said sole member, a shank stiffener having a perforation adjacent to its forward end through which said shank passes, and fastening elements for said stiffener extending into said sole member toward said head and within the area thereof on opposite sides of said shank portion.

9. A shoe comprising a sole member hav-

- ing a perforation adjacent to its "break" line, a headed fastener having its shank portion extending through said perforation, its head lying against one face of said sole member, a shank stiffener having a perforation adjacent to its forward end through which said shank passes, and fastening elements for said stiffener extending into said sole member toward said head and within 5 the area thereof, said shank portion being bent over the outer face of said stiffener.
10. A shoe comprising a sole member having a perforation adjacent to its "break" line, a headed fastener having its shank portion extending through said perforation, its head lying against one face of said sole member, a shank stiffener having a perforation adjacent to its forward end through which said shank passes, and fastening elements for said stiffener extending into said sole member toward said head and within 15 the area thereof on opposite sides of said shank portion, said shank portion being bent over the outer face of said stiffener.
20. 11. A shoe comprising an innersole having a perforation adjacent to its "break" line, a headed fastener having a two-part shank portion passed through said perforation, its head lying against the inner face 25 of said innersole, a shank stiffener engaging the outer face of said innersole and having a pair of integral prongs extending from one face thereof adjacent to one end and a perforation between said prongs 30 through which said shank portion passes, said prongs being embedded in said in- 35
- nersole within the area of said head, and the two parts of said shank portion projecting through said stiffener being separated and brought down against the outer face of 40 said stiffener.
12. A shoe comprising a sole member having a perforation therethrough, a headed fastener having its shank portion extending through said perforation and its head lying 45 against one face of said sole member, and a pronged stiffener having a perforation through which said shank passes, its prongs being clinched in said sole member within the area of said head. 50
13. A shoe comprising a sole member having a perforation therethrough, a headed fastener having its shank portion extending through said perforation and its head lying against one face of said sole member, and a pronged stiffener having a perforation through which said shank passes, its prongs being clinched in said sole member within 55 the area of said head, the shank of said fastener overlying said stiffener on the opposite side thereof from said head. 60
14. A shoe comprising a sole member, a headed member carried thereby and having its head lying against one face thereof, and a pronged stiffener on the opposite face of 65 said sole member and having its prongs clinched in said sole member within the area of said head.

In testimony whereof I have affixed my signature.

REINHARD E. BARTELS.
